(57) **CLAIM**

The ornamental design for a ring holder for electronic device as shown and described.

DESCRIPTION

FIG. 1 is a front, top, and left side perspective view of a ring holder for electronic device with ring in a closed position, showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a top, back, and right side perspective view thereof;

FIG. 9 is a front, top, and right side perspective view thereof in use; and,

FIG. 10 is a front, top, and right side perspective view of the ring holder for electronic device, shown with ring in an open position, in an environment of use.

The broken lines shown in FIGS. 9 and 10 depict environment and form no part of the claimed design.

1 Claim, 8 Drawing Sheets
